ALFRED ANDERSON, OF DETROIT CITY, MINNESOTA, ASSIGNOR OF ONE-FOURTH TO ASAHEL G. WEDGE, ONE-FOURTH TO HALVOR RASMUSSEN, AND ONE-FOURTH TO PETER K. HASLERUD, OF DETROIT CITY, MINNESOTA.

SWITCH OPERATING AND LOCKING MECHANISM.

No. 838,834.

Specification of Letters Patent.

Patented Dec. 18, 1906.

Application filed March 19, 1906. Serial No. 306,872.

To all whom it may concern:

Be it known that I, ALFRED ANDERSON, a citizen of the United States, residing at Detroit City, in the county of Becker and State of Minnesota, have invented certain new and useful Improvements in Switch Operating and Locking Mechanism, of which the following is a specification.

The object of my invention is to provide an improved switch-operating mechanism which is provided with means for automatically and securely locking the switch-points by direct engagement therewith and which embodies comparatively few and simple parts, which will be durable in construction and efficient in operation for the purposes for which they are intended.

The invention consists, essentially, of the combination with switch-points and their switch-bars of means for directly acting against the switch-points to hold them locked and means for actuating the switch-bar, the switch-bar-actuating means being so arranged that it will first throw the switch and then actuate the switch-point locks, one action being always antecedent to the other, so that the switch-locking means will be out of the way when the switch-points are moving from one side of the line to the other and their locking means only be brought into operative relation after they have been properly positioned. By this means it is insured that the switch-point-locking means will not interfere with the proper actuation or movement of the switch-points.

For a full description of the invention and the merits thereof and also to acquire a knowledge of the details of construction of the means for effecting the result reference is to be had to the following description and accompanying drawings, in which—

Figure 1 is a plan view of my improved switch operating and locking mechanism. Fig. 2 is a transverse view thereof on an enlarged scale and on the line $\alpha\alpha$ of Fig. 1. Figs. 3, 4, and 5 are bottom plan views illustrating the parts in different relative positions.

Corresponding and like parts are referred to in the following description and indicated in all the views of the drawings by the same reference characters.

Referring to the drawings, the numeral 1

designates the permanent rails of the track, and 2 the switch-points, connected to the switch-bar 3. 4 designates the head-block, and 5 the switch-stand mounted thereon. Supported by the switch-stand 5 is the vertical crank-shaft 6, provided with the usual operating-arm 7, having a hinged handle portion 8, designed to be thrown down into the usual sockets 9 on the switch-stand and preferably locked therein to hold the switch in either closed or open position. The switch-bar 3 is provided at its ends adjacent the switch-stand with a longitudinal slot 10, opening at its inner end into a short transverse slot 11. The switch-operating rod 12 is connected at one end to the crank of the shaft 6 and is provided at its opposite end with a pin 13, fitted to work in the slots 10 and 11, and said switch-operating rod 12 is also provided with a fork 14, one member of which is provided with a lateral extension 15, as shown. The shaft 16 is journaled alongside one of the permanent rails 1 and is preferably supported by the head-block 4 and the next adjacent tie, and said shaft is provided with a crank-arm 17, connected by a link 18 to a crank 19 on the end of a rock-shaft 20, said latter shaft being journaled in hangers and preferably extending across the track along that face of the tie carrying one end of the shaft 16 that is adjacent the head-block 4. The rock-shaft 20 has two radially-extending fingers 21, designed to be swung upwardly alongside of the switch-points in engagement therewith to lock the same when the rock-shaft 20 is turned about its longitudinal axis. It is to be understood that the rock-shaft 20 is actuated directly from the shaft 16 and indirectly by means of the crank-shaft 6 and switch-operating rod 12. To accomplish this result, the switch-operating rod 12 has its fork 14 embracing the shaft 16. A spring 22, coiled around said shaft 16, presses against the forked end of the switch-operating rod 12 in a direction to throw the same into the laterally-extending or transverse slot 11, and the shaft 16 is provided with oppositely-extending wings 23, between which the lateral extension 15 of the fork 14 has play.

In describing the practical operation of my improved switch-locking mechanism it will be assumed at the outset that the parts are in

the position shown in Fig. 3. If then the crank-shaft 6 be turned to throw the switch, the switch-operating rod 12 will draw the switch-bar 3 in the proper direction, with the 5 pin 13 seated in the transverse slot 11 and held in said slot by the action of the spring 22 upon the fork 14 of the operating-rod 12. By this movement of the switch-operating rod 12, which is the initial movement thereof to 10 throw the switch-points, the lateral extension 15 of the forked end of the said rod will leave its position under the adjacent wing 23 of the rock-shaft 20, but will have no effect upon said rock-shaft, the latter being now in 15 such a position that its fingers 21 will be depressed, and thus not interfere with the proper movement of the switch-points 2. As soon, however, as the switch-operating rod 12 has been moved sufficiently far to throw 20 the switch-points into their proper position, as illustrated in Fig. 4, with the pin 13 still seated in the transverse slot 11, the further movement of the operating-rod 12 in the same direction will cause the spring 22 to 25 yield and allow the pin 13 to come out of the transverse slot 11 and move in the longitudinal slot 10, so that the operating-rod 12 will have a relative movement independently of the switch-bar. (See Fig. 5.) This further 30 and relative independent movement of the throwing or operating mechanism results in the lateral extension 15 acting upon the other wing 23 to rock the shaft 16 and likewise the shaft 20 in the direction to raise the 35 fingers 21 alongside of and in contact with the switch-points, thereby securely locking the same. Conversely, a reverse movement of the switch-throwing mechanism will result in a limited independent movement thereof 40 with respect to the switch-bar 3, and this limited movement will result in first rocking the shaft 20 in the reverse direction to depress its fingers 21 until the pin 13 shall have come opposite the transverse slot 11, where- 45 upon the spring 22 will move the operating-rod 12 in a direction to cause the said pin to enter the transverse slot. Hence the continued movement of the switch-operating mechanism will then effect the movement of 50 the switch-points.

From the foregoing description, in connection with the accompanying drawings, it will be seen that I have provided simple and effective means for both throwing the switch-points and locking the same, such means embodying constructions and arrangements of the parts whereby the switch-throwing mechanism, while it serves the double function of throwing the switch-points and locking the 55 same will have a movement relative to both the switch-bar and the switch-point-locking devices, so that the throwing of the switch-points and the locking of the same will always be accomplished in two successive 60 movements by the same operating means—

namely, the switch-throwing mechanism. Hence there will always be insured that the switch-points are first thrown to the proper position before the locking-fingers are thrown up into engagement with the switch-points, and subsequently the latter will not interfere with the proper movement of the switch-points. 7c

Having thus described the invention, what is claimed as new is—

1. The combination with switch-points of a transverse rock-shaft provided with fingers designed to extend alongside of the switch-point to lock the same, said shaft being provided with a crank, a longitudinal shaft provided with a crank having a link connection with the other crank and also provided with oppositely-extending wings, a switch-bar connected to the switch-points and means for actuating said switch-bar to move the switch-points in one direction or the reverse, said means including a switch-operating rod arranged for a limited movement independently of the switch-bar and provided with a lateral extension adapted to contact with one or the other of said wings, for the purpose specified. 85

2. The combination with switch-points of means for locking the same, a switch-throwing mechanism arranged to also actuate the locking means, means whereby an initial movement of the switch-throwing means in one direction will throw the switch-points without moving the switch-locking means and whereby a continued movement of the switch-throwing mechanism will be permitted independently of the switch-points and actuate the switch-locking means. 95

3. Switch operating and locking mechanism comprising switch-points, a switch-bar secured thereto and provided with a longitudinal slot and a transverse slot opening at one end into each other, means for locking the switch-points, a switch-operating rod and means for actuating the same said rod being provided with a pin working in said slots a spring acting against said switch-operating rod in a direction to throw the pin into the transverse slot, whereby the operating-rod, when moving the switch-point in one direction will be permitted to have a continued movement independently thereof, and means whereby the operating-rod will actuate the locking means upon said independent movement. 110

4. Switch operating and locking mechanism, comprising switch-points, a switch-bar connected thereto and provided at one end with a longitudinal slot and with a transverse slot opening into each other at one end, a rock-shaft provided with fingers designed to extend up alongside of the switch-points to lock the same, a shaft operatively connected to said rock-shaft and provided with oppositely-extending wings, switch-throw- 125

130

ing mechanism including an operating-rod having a pin working in said slots and provided also with a lateral extension designed to engage said wings, and a spring tending to move said switch-operating rod in a direction to throw said pin into the transverse slot of the switch-bar.

- 5 5. Switch operating and locking mechanism, comprising switch-points provided with a switch-bar, said bar being formed at one end with a longitudinal slot and a transverse slot opening into each other at one end, a rock-shaft provided with fingers designed to extend up alongside of the switch-points 10 to lock the same, a shaft 16 having a crank and link connection with the rock-shaft to actuate the same and provided with oppositely-extending wings, switch-throwing mechanism including an operating-rod provided 15 with a forked end designed to embrace said shaft 16 and also provided with a pin working in said slots and with a lateral extension designed to engage with said wings, and a spring coiled around the shaft 16 and adapted 20 to bear against the forked end of the operating-rod in a direction to throw the pin into the transverse slot.

- 25 6. The combination with switch-points of means for locking the same, said means including a longitudinally-extending shaft 16 provided with oppositely-extending wings,

a switch-bar connected to said switch-points, a switch-actuating rod provided with a lateral extension adapted to act against one or the other of said wings to move the switch-locking mechanism in one direction or the reverse, and means whereby the initial movement of the switch-actuating rod in one direction will throw the switch-points without contact between the lateral extension and said wings and whereby a continued movement of the switch-throwing mechanism in the same direction will cause the contact of said extension with one of said wings to actuate the switch-locking means. 35 40 45

7. The combination with switch-points of locking means therefor including a longitudinally-extending shaft provided with oppositely-extending wings, a switch-bar connected to said switch-points, and a switch-actuating rod connected to said switch-bar and arranged for an initial movement independent of the switch-bar, said rod being provided with means for engaging said wings to actuate the switch-locking means. 50 55

In testimony whereof I affix my signature in presence of two witnesses.
